UNITED STATES PATENT OFFICE.

DILL CHAPMAN, OF LA JUNTA, COLORADO.

SYSTEM OF WATER DISTRIBUTION.

1,234,625.

Specification of Letters Patent. Patented July 24, 1917.

Application filed August 5, 1916. Serial No. 113,364.

To all whom it may concern:

Be it known that I, DILL CHAPMAN, a citizen of the United States of America, residing at La Junta, in the county of Otero and 5 State of Colorado, have invented a new and Improved System of Water Distribution, of which the following is a specification.

My present invention relates to an improved system of water distribution, and is 10 particularly applicable for use in connection with railway passenger trains, for the purpose of supplying water for various purposes to each car of the passenger train from a central or main supply tank, preferably carried by the tender of the locomotive 15 pulling the train.

The primary object of the invention is to provide a system of water distribution especially applicable for railway passenger train 20 service which will provide a reliable supply of fresh water to be used for drinking, culinary, or other purposes, and which system is capable of extension or contraction according to the number of cars used in the train. 25 By the utilization of my system, a great saving is attained, both as to time and labor. In the present mode of watering cars of a railway passenger train, the services of several men are required to fill the tanks of the 30 separate cars, and this mode of filling the tanks requires the expenditure of much time and labor, and which will be readily understood by those familiar with railway traffic. When a passenger train is equipped with my 35 system of water distribution, many delays are avoided, and objectionable features are eliminated, and a comparatively perfect and reliable system of water distribution is provided.

40 In the accompanying drawings I have illustrated one complete example of the physical embodiment of my invention constructed and arranged according to the best mode I have so far devised for the practical 45 application of the principles of my invention, but it will be understood that the embodiment and arrangement are subject to variation within the scope of my claim without departing from the spirit of my invention.

50 Figure 1 is a diagrammatic illustration of a railway train, showing the locomotive and two passenger cars equipped with my system of water distribution.

55 Fig. 2 is a vertical, sectional view showing the main reservoir carried by the locomotive

tender, and one of the tanks, two of which are carried by each car, and the flexible hose coupling between the tender and a car or between two cars, is also illustrated in this 60 view.

My system of water distribution is adapted for passenger trains comprising various numbers of cars, but for convenience of illustration, I have shown the locomotive as 1, 65 and the two passenger cars designated as 2 and 3. Of course, the number of cars may be increased or decreased within limits of the capacity of the engine or locomotive 1.

The locomotive tender 1^a I equip with a 70 main reservoir 4, and this reservoir supplies the water tanks 5 and 5' carried by the passenger cars. If desired, only one tank may be used for each car, but preferably a tank 5, and a similar tank 5' are carried at 75 the respective ends of the cars. For dining cars, or other cars adapted for special purposes, the arrangement of the water tank will be varied as understood.

The reservoir 4 is located at a point on 80 the locomotive tender as high as can be secured, without infringing upon the limited height of the locomotive or passenger cars, and this reservoir is adapted to be filled with water and is provided, for sanitary 85 purposes, with a cover 6. An outlet pipe 7 in the reservoir is controlled by a valve 8, and this pipe is adapted to supply water from the main reservoir through the flexible coupling indicated at 9, 10, 11, and 12, 90 and the coupling connects this outlet pipe 7 with the main pipe 13 carried by each car. The flexible coupling between the tender and first car, as well as between other cars, is of standard type, and comprises the usual 95 hose coupling similar to the steam or air couplings between the cars of standard railroads.

The main pipe 13 is preferably located on 100 the interior of the cars and runs along the corner of the car between its side wall and the floor, and preferably in juxtaposition to the steam pipe line of the railway train, in order to prevent freezing of the water in winter. The main pipe is controlled by a 105 pair of valves 13' and 13", one located at each end of the car, and when the car is detached from a train, these valves being closed, the supply of water is retained in the tanks 5 and 5'. Each tank is fitted with a 110 branch pipe as 14, 14' by which the tank is connected to the main pipe 13, and a valve 15

controls the supply of water to the tank 5 or 5'. Each of the tanks is equipped with an outlet faucet 16 which is preferably at the lower end of the tank, from which water 5 may be drawn for any desired purpose.

The tanks 5 and 5' are all closed in order to prevent waste of water therefrom, because of the fact that the reservoir is located at a higher altitude than the tanks. With all 10 of the valves except the valves 16 and the last valve 13^a at the rear end of the train open, it will be seen that a supply of water is maintained throughout the entire train of cars, and when the water is drawn from 15 one tank, the supply is automatically replenished as long as the water remains in the reservoir 4. Preferably, the valve or faucet 13^a at the rear end of the train, is "cracked," or left slightly open, in order to permit an 20 infinitesimal waste of water therethrough in order to insure a continuous circulation. However, under ordinary conditions it will be seen that as water is drawn from the various tanks 5 and 5', a circulation will be induced as a matter of course throughout the 25 entire system. When a car is to be detached from a train, the hose coupling is released at 10 at both ends of the car, the two valves 13' and 13^a having previously been closed. 30 Thus, a car may be cut out from a train

and still retain its water supply. In coupling up the cars to make up a train, the hose couplings are secured between the cars at 10, and then when the valves are opened throughout the system, the water will be distributed and the entire train equipped with the required supply. 35

From the above description taken in connection with my drawings it is evident that I have provided a system of water distribution for use in railway equipments, which fulfills the functions of a comparatively perfect system and will secure the objects heretofore stated, and eliminates the numerous objections to the present system of water distribution throughout passenger trains. 40 45

What I claim is:

A system of water distribution for railway passenger trains comprising a main elevated reservoir, smaller sealed tanks carried by the several cars of the train the tops of which are below the bottom of the reservoir, a main pipe from the reservoir to the several cars, and branch pipes from the main pipe to the tops of the tanks whereby the tanks are automatically kept full and the water in which is under pressure of the full weight of the water in the reservoir. 50 55

In testimony whereof I affix my signature.
DILL CHAPMAN.
